UNITED STATES PATENT OFFICE.

ROY WRIGHT, OF STRYKER, OHIO.

BROODER STOVE.

Application filed September 2, 1925. Serial No. 54,032.

This invention relates to stoves, but is more particularly concerned with brooder stoves of the wickless type.

Objects of this invention are to provide in connection with a brooder stove temperature controlled means for regulating the action or operation of the burner in such a manner that the temperature within the room in which the stove is positioned is maintained constant; to provide a thermostatic device which is adapted to raise or lower the burner relatively to the supply reservoir for varying the amount of fuel supplied to the burner; and to provide a brooder stove having the new and improved features of construction, arrangement and operation hereinafter described.

The invention is shown by way of illustration in the accompanying drawings, in which,

Fig. 1 is a perspective view of the brooder stove; Fig. 2 is an elevation partly in section of the burner; and Fig. 3 is a vertical sectional view of the fuel supply reservoir.

The illustrated embodiment of the invention comprises a sheet metal U-shaped support 1 having edge flanges 2 for securing the support in the desired position. Mounted on one end of the support 1 is a reservoir for oil or the fuel, and in this instance the reservoir comprises a bowl 3 having a ring 4 provided with depending arms 5 which are pivoted at their lower ends to the upper portion of the support 1. The ring 4 is adapted to receive and support an inverted jar 6 containing the oil or other fuel and formed on the jar 6 is a neck 7. It will readily be apparent that the height of liquid level in the bowl 3 is controlled by the neck 7. From the reservoir the liquid fuel flows through a pipe 8 which extends downwardly from the bowl 3 through an opening 9 in a support 1, then extends horizontally beneath the support 1 and upwardly through an opening 10 in the support, the end portion of the pipe being connected to the burner 11. The burner 11 may be of any suitable form, but, in this instance is provided with an annular chamber 12 in which asbestos packing, or other similar substance, may be placed, and as will readily be understood, this substance is saturated with liquid fuel from the reservoir and ignited. Mounted in any suitable manner over the burner 11 is a frusto-coni-

cally shaped shade or hood 13 which serves as a shield for the burner flame.

In accordance with this invention, thermostatic means is provided for raising and lowering the burner 11 relatively to the reservoir so that a greater or less amount of fuel is supplied to the burner in accordance with the requirements of service. It will, of course, be understood that in the use of stoves of this character it is desired to maintain the temperature within the room approximately at a certain predetermined degree so that the chicks will not be injured as a result of too great or too low a temperature.

For accomplishing this purpose, a lever 14 is pivoted intermediate its ends to a bracket 15 which is supported on the top of the sheet metal support 1. The outer end of the lever 14 engages the underside of the burner 11 and mounted on the inner end portion of the lever is a sliding weight 16 which serves as a counterbalance and may be adjusted to the proper position. The outer end of the lever 14 is connected by means of a rod 17 to the pipe 8 as shown, and it will be seen that clock-wise movement of the lever 14 elevates the burner 11, and counter-clockwise movement of the lever lowers the burner, this lowering action being insured by means of the rod 17.

Suitably mounted on the support 1 is a thermostatic plate 18 provided with an upstanding pin 19, and this plate may be of any suitable construction which is adapted to snap from one position to another at different predetermined temperatures. For example, this thermostat may be constructed to expand at a certain predetermined high temperature and contract at a predetermined low temperature, or it may be so constructed as to change from a normally convex position to a concave position at the desired temperatures. Thermostats of the above construction are well known in the art and may consist of two metals having different coefficients of expansion as to be actionable at the desired temperatures. In view of the fact that the construction of the thermostat forms no part of the present invention, further description thereof is deemed unnecessary.

The action of the thermostat 18 is transmitted through a pin 19 to a screw 20 in the lever 14 so that movement of the thermo-

stat in one direction raises one end of the lever 14, which in turn elevates the burner 11 and pipe 8 to diminish or completely shut off the fuel supply from the reservoir. It will be seen that adjustment of the screw 20 operates to regulate the movement of the burner 11. Connected to the lever 14 between the screw 20 and burner 11 is a screw 21 which is adapted to engage the top of 10 the support 1, and this screw serves to adjust the normal level of the fuel in the burner 11.

When it is desired to discontinue the operation of the stove, the lever 14 may be 15 moved into engagement with a catch 22 on the sheet metal support 1, a notch 23 being formed in one end of the lever for engagement with the catch.

While I have shown and described a construction which is the best form known to me at the present time, it is to be understood that numerous changes in details of construction and arrangement may be effected without departing from the spirit of the 25 invention, especially as defined in the appended claims.

What I claim is:

1. In a device of the class described, a burner, a fuel supply reservoir, rigid con-

nexion between said reservoir and burner, means for pivotally mounting said reservoir, a lever adapted to engage the underside of said burner, means for pivoting said lever intermediate the ends thereof, a thermostatic device adapted to move said lever at different predetermined temperatures, adjustable means on said lever for varying the amount of oil normally supplied to said burner, and an adjustable counter-balance on the opposite end of said lever. 30

2. In a device of the class described, a burner, a fuel supply reservoir, rigid connection between said reservoir and burner, a lever adapted to engage the underside of said burner, means for pivoting said lever intermediate the ends thereof, a thermostatic device adapted to move said lever at different predetermined temperatures, adjustable means on said lever for varying the amount of oil normally supplied to said burner, an 45 adjustable counter-balance on the opposite end of said lever, and a catch adapted to engage the end of said lever adjacent said counter-balance for holding said burner in inoperative position. 50

In testimony whereof I have hereunto signed my name to this specification.

ROY WRIGHT.
